Patented Feb. 25, 1919.

INVENTION

Theodor D. Fisher

Carl P. Goepel

ATTORNEY

UNITED STATES PATENT OFFICE.

THEODOR D. EISNER, OF WOODHAVEN, NEW YORK.

SUPPORT FOR EMBROIDERY-FRAMES.

1,295,140.

Specification of Letters Patent. Patented Feb. 25, 1919.

Application filed July 20, 1917. Serial No. 181,775.

To all whom it may concern:

Be it known that I, THEODOR D. EISNER, a citizen of the United States, and resident of Long Island, in the State of New York, city 5 of Woodhaven, have invented certain new and useful Improvements in Supports for Embroidery-Frames, of which the following is a specification.

The present invention relates to improvements in supports for embroidery frames, and particularly such supports as are used in embroidery machines. An object of the invention is to provide such a support which will permit of the quick insertion and removal of the frames, will receive the exact positioning of the frames, and will support the frames rigidly and securely. Another object is to provide such a support which will be simple and inexpensive in construction, and may be readily and conveniently installed in the embroidery machines.

With these and other objects in view, embodiments of my invention are shown in the accompanying drawings, and these embodiments will be hereinafter more fully described with reference thereto, and finally pointed out in the claims.

In the accompanying drawings:

Figure 1 is a front elevation of my improved support, showing a frame inserted therewith with parts broken away;

Fig. 2 is a vertical sectional view along the line 2—2 of Fig. 2;

Fig. 3 is a top view thereof; and

Fig. 4 is a perspective view of a slightly modified form of construction.

Similar reference characters indicate corresponding parts throughout the several figures of the drawings.

Referring to the drawings, the embodiment of my invention illustrated, comprises a lower member and an upper member, which are mounted in the embroidering machine in spaced relation, the lower member 45 consisting of a longitudinally disposed right angle bar 10, provided at suitable distances with U-shaped holding members 11 secured thereto by rivets 12, countersunk at their inner side, and forming at the front of the bar 50 upstanding lugs.

The embroidery frame, which is shown diagrammatically, consists of two longitudinal rails 13 and 14, and connected by transverse cross pieces 15.

55 The upper supporting member comprises an angle bar 24, open at its forward side to

permit of insertion of the frame therein, and provided in spaced relation along its upper surface with hinged supporting members 25, hingedly mounted upon a member 26, secured by rivets 27 to the angle bar, and provided at their ends with clamping members 28, bent downwardly at each side as at 29 and 30, the forward portion 30 being relatively longer than the portion 29. These 65 clamping members are adapted to be moved downwardly to embrace the angle bar, as clearly indicated in dotted lines in Fig. 1, to lock the frame in place.

The portions 30 of the clamping members 70 are all pivotally connected at 31 to a longitudinal bar 32, provided at an intermediate portion thereof with a hinged handle 33, preferably secured by one of the rivets pivotally connecting the bar 32 to one of the 75 clamping members, and which may be folded flat against the bar when not in use, and when it is desired to swing the bar, may be moved outwardly into the position shown in dotted lines in Fig. 3. 80

A positioning strip 16 is secured to the upper rail 14, and extends outwardly therefrom to form a projecting lug. The positioning strip, in addition to being secured by screws 17, is held in place by a plate 18, 85 and secured by screws 19. The plate 18 extends over the sides of the rail as at 20, and is secured by screws 21, a cut out portion 22 being provided therein to engage about the projecting strip. The positioning strip and 90 plate are countersunk.

A recess 23 is provided in the front edge of the bar 24, and in placing the frame in the support, the projecting lug 16 is engaged therein, thus properly positioning the 95 frame and preventing any longitudinal movement thereof.

The upper angle bar 24 is supported from a bar or girder 50 and is adjustably connected thereto by means of hangers 51 having perpendicular slots 52 therein, in which are engaged set screws 53 provided on the bar 24, thus permitting of the vertical adjustment of the bar 24.

At the ends of the bar 24 there are provided adjustable angle pieces 54 which form stops for the frames. The angle pieces are secured by a set screw 55 passing through a slot 56 therein which permits of their adjustment. 105

The operation of my improved support is as follows: The embroidery frame, in 110

which there is spanned material to be embroidered, is first inserted in the lower member, the positioning strip 16 being engaged in the recess 23 of the bar 10. The upper portion of the frame is inserted in the open side of the bar 24, the clamping members being swung up as shown in full lines in Fig. 1, to permit of such insertion. By engaging the handle and turning the longitudinal bar downwardly, all of the clamping members are simultaneously brought into engagement with the bar 24, the portions 30 of the said members engaging the front face of the embroidery frame, and locking the same in the support. The frame, it will be seen, is quickly inserted and removed, and when inserted is substantially held from movement, so that the embroidery operation may be carried on in a perfect manner.

If desired, the intermediate portion of the bar 24 may be omitted, this being desirable where very long embroidery frames are used, and in certain types of embroidery machines.

In Fig. 4, I have shown a slightly modified form of construction, in which the clamping members are formed of wire, as at 34, being pivotally mounted in a grooved plate 35, secured to the rail 24, the forward side of the clamping member being relatively longer than the inner side, and bent outwardly at its extremity 36 where it is pivotally engaged by a longitudinal bar 37. A handle 38 is formed on the end of the clamping member. The same operates in a manner similar to that described with reference to the foregoing embodiment of my invention.

I have illustrated preferred and satisfac-

tory embodiments of my invention, but it is obvious that changes may be made therein within the spirit and scope thereof, as defined in the appended claims.

I claim:

1. In a frame support, comprising spaced supporting members, one of said members having an open side to permit insertion of the frame therein, a plurality of pivoted clamping members for closing said open side having their swinging axes above said frame and transverse to the longitudinal axes of said supporting members, and unitary means connecting said clamping members to permit of the simultaneous swinging thereof.

2. An embroidery frame support comprising a beam provided at intervals with dependent hangers having vertical slots, spaced supporting members, one of said members having an open side to permit insertion of the frame therein and being provided with clamping screws adjustably engaging said slotted hangers, and a plurality of pivoted frame retaining means mounted on said open side supporting member.

3. An embroidery frame support comprising spaced members whereof one has an open side to permit the insertion of the frame, a plurality of arms hinged at intervals to the top of said open side member and severally provided at their outer ends with U-shaped clamps adapted to embrace said member together with the upper part of said frame when in locked position, and a longitudinal actuating rod pivoted to the outer wings of said U-shaped clamps.

In testimony that I claim the foregoing as my invention, I have signed my name.

THEODOR D. EISNER.
